UNITED STATES PATENT OFFICE.

GUSTAV DREWS, OF NEW YORK, N. Y.

BOOK-SUPPORT.

1,245,206.

Specification of Letters Patent.

Patented Nov. 6, 1917.

Application filed December 5, 1914, Serial No. 875,692. Renewed April 6, 1917. Serial No. 160,311.

To all whom it may concern:

Be it known that I, GUSTAV DREWS, a citizen of the United States, residing in New York, in the county of Kings and State of New York, have invented certain new and useful Improvements in Book-Supports, of which the following is a specification.

This invention relates to and has for its main objects to provide a book support that will hold an open book at an angle in position for reading; also to provide a device that can be folded together thus to facilitate shipping, and for the convenience of home or office to pack away in a drawer or on a library shelf; it is also intended to provide a device that is made of substantially two pieces, and one that will support itself in open position at the proper angle without the use of any breakable parts; and it is further intended to provide a means for holding down the leaves on such support.

A specific construction embodying this invention is illustrated in the accompanying drawings in which—

25 Figure 1 is a view in perspective of an embodiment of the invention in open position.

Fig. 2 is an end view of the same in open position.

30 Fig. 3 is an end view of the same in closed or folded up position.

Fig. 4 is a plan view of one section of the support detached.

Fig. 5 is a cross-section on the line 5—5 of Fig. 4.

35 Fig. 6 is a plan of one section of a modification; and Fig. 7 is a cross section of the same on the line 7—7 of Fig. 6.

In the construction shown, two plates 5 and 6 are hinged together by hinges 7 and 8. These hinged plates may be of wood or stamped, cut or cast out of metal. In conformation, they are practically identical, so it will suffice to describe but one of them.

40 A rear extension 9 is provided, substantially triangular, the base 10 of which extends from the middle of the main plate, the hypotenuse 11 extending from the outer edge of the base to the outer edge of the main plate, thus leaving a right angular recess as clearly shown in Fig. 4. The edge 12 of the main plate in this recess or cut-away portion

45 is beveled. When the device is open for use, this beveled edge 12 rests against the extension 9 of plate 5. These beveled edges 12, 12 resting against the extensions 9, 9

actually receive the load carried by the support, thereby saving the hinges and incidentally serving to give a neat, close fit to the support when opened, and to permit free 60 operation of the hinges. The portion of the support resting on the table is a corner of one of the extensions and the hypotenuse 11 of the other extension. As is obvious, by making these plates with their extensions 65 identical, the support can be reversed and set up in position, the same one way as the other.

To prevent the book from slipping down onto the table, ledges 13 may be provided. 70 These can be provided at the upper and lower edges of the plates for the purpose of using the support as a reversible device. In the present instance, ledges 13, 13 are provided only at the lower edges of the plates. 75

Obviously if the device is not to be used as a reversible device, the conformation of one of the extensions 9, the one which when in use only engages the resting surface with its corner, may be of any other suitable conformation. 80

It is also to be noted that the inclination of the support may be adjusted as desired by merely changing the length of one extension or by changing the length and inclination of the hypotenuse of the extensions, or by placing a book or other object under the corner of the extension. 85

A means for holding down the leaves of the book are provided. In the construction shown, there is provided a portion 14 rolled over from each of the ledges 13. In this portion 14 is pivotally secured the end of a wire 15. When the book is folded up, these wires are turned down below the lower edges 95 of the plates. When the book is open, the wires are turned up to engage any part of the leaves. When the support is closed, these wires may be positioned between the plates 5 and 6, the tail pieces 16 serving to 100 spring-press the wires in closed position.

Obviously when the device is made of sheet metal as shown in Figs. 6 and 7, a rolled formation 12' is substituted for the beveled edge 12, of the construction shown in 105 Fig. 1, and a hinge portion 7' is formed integral with the main plates, instead of using separate hinges.

Although but one specific embodiment of this invention is herein shown, it will be understood that numerous details of the construction shown could be altered or omitted 110

without departing from the spirit of this invention.

Having thus described my invention, what I claim as new and desire to secure by Letters Patent is:

1. A support comprising two plates hinged together, each plate having a rear extension, the extensions passing one another when the plates are opened into supporting position, a portion of each plate extending across and resting on the rear extension of the other plate when the plates are opened so that the plates lock one another in open position.
2. In a book support comprising two plates hinged together, each plate having an extension extending from one-half of the rear edge of the plate, said extension being of triangular conformation, the remaining half of each plate extending across and resting on the extension of the other plate when the plates are opened so that the plates lock one another in open position.
3. In a book support comprising two plates hinged together, each plate having a rear extension in its plane in the form of a right-angled triangle projecting from the hinged edge of the plate for half the length of said edge, the hypotenuse forming one of the sides of the projection, the plates in open position resting on these rear extensions, one of the extensions adapted to engage the resting surface with its corner and the other extension adapted to engage the resting surface with its hypotenuse.
4. A reversible book support comprising two plates pivoted to one another, each plate having a rear extension, the rear extension being of right triangular conformation so that when the support is open both the corner of one of the extensions and the hypotenuse of the other engage the resting surface.
5. A book support comprising two plates hinged to one another, a rear extension on each plate, a portion of each plate resting on the rear extension of the other plate when the plates are opened so that the plates lock one another in open position, means preventing the book supported from slipping down, and means for holding the leaves.
6. A two-piece collapsible book support that can be opened where it will support itself in an inclined position and can also be folded together, said support comprising two plates pivotally connected to one another, rear extensions on said plates and in the planes thereof, the extensions each having one side beginning substantially at the middle of the edge from which it extends, said plates in open position being supported by said extensions.
7. A two-piece collapsible book support that can be opened where it will support itself in inclined position and can also be folded together, said support comprising two plates pivotally connected to one another along opposing edges, said plates having rear extensions extending from said opposing edges and in the planes of said plates, the extensions each having one side beginning substantially at the middle of the edge from which it extends, said plates in open position being supported by said extensions, each of said extensions extending under and across the opposing edge of the other plate and contacting with the same, the extensions thus also acting as stops to prevent the plates from swinging clear around on their pivotal connection but lock them at an angle to one another where they are ready to receive an open book.
8. A book support comprising plates pivotally connected to one another and rear extensions on said plates, the extensions passing one another when the plates are opened into supporting position, and portions of the plates extending across and resting on said extensions when the plates are opened so that the plates lock one another in open position.
9. A book support comprising plates anchored to one another and rear extensions on said plates, the extensions projecting in different directions, and the plates extending across and resting on said extensions in supporting position so that the plates lock one another.

GUSTAV DREWS.
